(57) **CLAIM**

The ornamental design for an IP desktop phone, as shown and described.

DESCRIPTION

FIG. 1 is a front view of a first embodiment of an IP desktop phone showing my new design;
 FIG. 2 is a back view thereof;
 FIG. 3 is a left view thereof;
 FIG. 4 is a right view thereof;
 FIG. 5 is a top view thereof;
 FIG. 6 is a bottom view thereof;
 FIG. 7 is a perspective view thereof;
 FIG. 8 is another perspective view thereof with a phone receiver illustrated in broken lines;
 FIG. 9 is another front view of the first embodiment, with the display shown in an alternate position for use;
 FIG. 10 is a back view thereof;
 FIG. 11 is a left view thereof;
 FIG. 12 is a right view thereof;
 FIG. 13 is a top view thereof;
 FIG. 14 is a bottom view thereof;
 FIG. 15 is a perspective view thereof;
 FIG. 16 is another perspective view thereof with the phone receiver illustrated in broken lines;
 FIG. 17 is a front view of a second embodiment of the IP desktop phone;
 FIG. 18 is a back view thereof;
 FIG. 19 is a left view thereof;
 FIG. 20 is a right view thereof;
 FIG. 21 is a top view thereof;
 FIG. 22 is a bottom view thereof;
 FIG. 23 is a perspective view thereof;
 FIG. 24 is another perspective view thereof with the phone receiver illustrated in broken lines;
 FIG. 25 is another front view of the second embodiment, with the display shown in an alternate position for use;
 FIG. 26 is a back view thereof;
 FIG. 27 is a left view thereof;
 FIG. 28 is a right view thereof;
 FIG. 29 is a top view thereof;
 FIG. 30 is a bottom view thereof;
 FIG. 31 is a perspective view thereof;

FIG. 32 is another perspective view thereof with the phone receiver illustrated in broken lines;
 FIG. 33 is a front view of a third embodiment of the IP desktop phone with the display shown in the same position for use as what is shown in FIGS. 25-32, the only deviation from the second embodiment is the shape of the number-pad buttons;
 FIG. 34 is a back view thereof;
 FIG. 35 is a left view thereof;
 FIG. 36 is a right view thereof;
 FIG. 37 is a top view thereof;
 FIG. 38 is a bottom view thereof;
 FIG. 39 is a perspective view thereof;
 FIG. 40 is another perspective view thereof with the phone receiver illustrated in broken lines;
 FIG. 41 is a front view of a fourth embodiment of the IP desktop phone;
 FIG. 42 is a back view thereof;
 FIG. 43 is a left view thereof;
 FIG. 44 is a right view thereof;
 FIG. 45 is a top view thereof;
 FIG. 46 is a bottom view thereof;
 FIG. 47 is a perspective view thereof;
 FIG. 48 is another perspective view thereof with the phone receiver illustrated in broken lines;
 FIG. 49 is another front view of the fourth embodiment, with the display shown in an alternate position for use;
 FIG. 50 is a back view thereof;
 FIG. 51 is a left view thereof;
 FIG. 52 is a right view thereof;
 FIG. 53 is a top view thereof;
 FIG. 54 is a bottom view thereof;
 FIG. 55 is a perspective view thereof;
 FIG. 56 is another perspective view thereof with the phone receiver illustrated in broken lines;
 FIG. 57 is a front view of a fifth embodiment of the IP desktop phone;
 FIG. 58 is a back view thereof;
 FIG. 59 is a left view thereof;
 FIG. 60 is a right view thereof;
 FIG. 61 is a top view thereof;
 FIG. 62 is a bottom view thereof;
 FIG. 63 is a perspective view thereof;
 FIG. 64 is another perspective view thereof with the phone receiver illustrated in broken lines;
 FIG. 65 is another front view of the fifth embodiment, with the display shown in an alternate position for use;
 FIG. 66 is a back view thereof;
 FIG. 67 is a left view thereof;
 FIG. 68 is a right view thereof;
 FIG. 69 is a top view thereof;
 FIG. 70 is a bottom view thereof;
 FIG. 71 is a perspective view thereof; and,
 FIG. 72 is another perspective view thereof with the phone receiver illustrated in broken lines.

The broken lines showing the phone receiver depict environmental subject matter only and form no part of the claim, while all other broken lines in the drawings depict portions of the IP desktop phone that form no part of the claimed design.
